CLAIM

The ornamental design for a lidded container, as shown and described.

DESCRIPTION

FIG. 1 is a perspective view of a lidded container showing our new design from the front, right side and top, with two of the lid clamping clips thereof released and the carrying handle thereof raised;

FIG. 2 is a front elevational view thereof with the lid clamping clips thereof fastened and the carrying handle thereof lowered;

FIG. 3 is a right side elevational view thereof;

FIG. 4 is a rear elevational view thereof;

FIG. 5 is a top plan view thereof;

FIG. 6 is a bottom plan view thereof; and,

FIG. 7 is a perspective view thereof from the same direction as FIG. 1, with the lid thereof exploded away from the body thereof.

The left side has an expected appearance, given the views shown. The internal cavity of the body thereof and the underside recess of the lid thereof are plain and unornamented.
